UNITED STATES PATENT OFFICE.

ROY ALEXANDER WEAGANT, OF NEW YORK, N. Y., ASSIGNOR, BY MESNE ASSIGNMENTS, TO RADIO CORPORATION OF AMERICA, A CORPORATION OF DELAWARE.

RADIOSIGNALING APPARATUS.

1,356,751.

Specification of Letters Patent. Patented Oct. 26, 1920.

Application filed July 12, 1918. Serial No. 244,562.

To all whom it may concern:

Be it known that I, Roy ALEXANDER WEAGANT, a citizen of the United States, and resident of Douglas Manor, county of 5 Queens, city and State of New York, have invented certain new and useful Improvements in Radiosignaling Apparatus, of which the following is a specification, accompanied by drawings.

10 This invention relates to radio signaling apparatus of the same general character as that shown in my co-pending applications Serial Nos. 157,594 and 181,458, in which I have disclosed my discoveries as to the over-head source or sources of propagation of static disturbances and described and claimed new methods and apparatus based upon such discoveries for eliminating static effects.

20 The primary object of the present invention is to still further improve upon that form of my apparatus in which separated antennæ, preferably in the form of loops or cages, are employed, connected by long 25 leads to a central receiving apparatus, for balancing out static while retaining the signals, although some of my improvements are applicable as well to other forms of apparatus.

30 In working with spacing between relatively small antennæ of the order of quarter-wave-length, half-wave-length, and greater, difficulty is experienced because of the great length of the leads, which pick up 35 both static and signals to an extent comparable with the antennæ, and one object of this invention is to reduce the troubles due to the leads by so constructing them that they pick up as little signal and static as possible.

40 I have also found that the best results are usually obtained by tuning at both ends, or substantially at the ends, of the long leads connecting the cages to the receiving apparatus, and I preferably provide local tuning 45 means for tuning the cages to the incoming signal waves, and preferably independent tuning means in connection with the receiving apparatus. The large distributed capacity of the leads and the complicated 50 nature of the propagation of the oscillations therein seems to require the local tuning means at the cages.

55 Certain obscure and not as yet thoroughly understood mutual effects also appear to exist between the leads and the cages, which

are apt to cause trouble in the proper functioning of the system, and may partly account for any residuum of static found remaining at the balance point. The difficulty may lie in the fact that the leads possess distributed inductance and capacity while the antennæ loops act as localized inductances of large magnitude, which are local energy gatherers. Currents due to both signals and static are apparently generated in the leads, in the cages, and in the receiving apparatus, in definite directions, so that there is a best or preferable relation of the leads to the cages and to the receiving apparatus in point of electrical connection, 60 and another important object of this invention is to provide means for determining the relative directions of current flow in the leads and in the cages and receiving apparatus respectively, so that these elements 65 of the system will coöperate electrically in balancing out static while retaining and adding the signals.

A further object of the invention is to 70 reduce or eliminate the troublesome effects which may be termed "spurious effects," due to the picking up of both static and signals by the apparatus in the receiving station itself. Since the spurious effects which interfere with the balance appear 75 even when the receiving apparatus is not connected to any circuit or collector outside the receiving house, they are increased probably by electro-static or electro-magnetic coupling between the leads and different 80 portions of the apparatus in the house, when the leads are connected to the receiving apparatus in operation. These "spurious effects" 85 may be due to other unknown or not well understood causes, but I am enabled 90 to very largely eliminate them by the preventive measures to be herein described.

In the absence of remote control for automatically controlling the tuning means and 100 electrical connections for the cages, some suitable means of communication should be provided to enable the operator at the central receiving station to communicate with the operators stationed at the cages, and for 105 this purpose I preferably utilize the leads as a convenient means of telephonic communication, so that the operators at the cages may be directed in making adjustments of the cages simultaneously with the reception 110 of signals at the central station. Separate

telephone lines or other means of communication may be provided if desired.

Further objects of the invention will hereinafter appear and the invention is illustrated in the accompanying drawings in which—

Figure 1 is a diagrammatic representation in perspective of a receiving system showing two separated cages and the central receiving house.

Fig. 2 is a similar view of a modification.

Fig. 3 is an enlarged detail perspective view of one of the cages, showing the tuning means for the cage and the controllable connections between the leads and the cage;

Fig. 4 is a diagrammatic representation of the circuits and connections for the system, as shown in Fig. 1, and

Fig. 5 is a perspective view of a modified form of cage.

Referring to the drawings, and at first more particularly to Fig. 1, A represents a receiving house and B are antennæ shown in the form of loops or cages connected by the leads C to suitable receiving apparatus in the receiving house. The leads are shown broken in their length to indicate that they are longer in proportion than actually shown, owing to the limitations of the sheet on which they are drawn. Small shelters or houses, D, are shown adjacent to the cages for housing the tuning and controlling apparatus for the cages. The cages B are preferably separated from one another by an appreciable fraction of a wave length in the general direction of desired reception and I am thus enabled to balance out static, and retain the signals which are out of phase, as fully set forth in my co-pending applications referred to.

The loop antennæ or cages may be of any suitable construction, but I have obtained excellent results in accordance with my invention in receiving over long distances through heavy static with cages constructed substantially as shown in the figures. In the enlarged detail view of Fig. 3 the three, thirty-foot poles H are about one-hundred and fifty feet apart, making the cage about three hundred feet in length. The cross arms J are spaced about twenty feet apart in a vertical direction and preferably provided with insulators K over which is wound approximately 7680 feet of No. 10 B. & S. hard-drawn copper wire, making twelve loops or turns L in all, with six loops at each side of the center, all the loops being preferably wound in the same direction. According to the construction shown, the upper cross-arms J are about twenty-five feet above the ground, but the height and number of poles, their spacing, the distance between cross-arms and the number and arrangement of loops, and length of wire used for the cages may all be varied as de-

sired, in accordance with the conditions met with, and depending upon the length of wave on which it is desired to receive, and the effective separation or fractional wave length spacing between cages.

The leads C connecting the cages to the receiving apparatus at the receiving house should preferably be arranged close together, as for instance, several inches apart, in a substantially horizontal plane, for under those conditions the leads seem to pick up the least amount of static. A convenient construction is to support the leads C at each side of the stakes O, formed of about two inch or three inch stock and spaced at suitable intervals along the line, as shown in Fig. 1. The leads may be near the ground, as shown, or elevated on higher stakes or poles E (shown in Fig. 2) as a matter of convenience, to permit passing under without interference. I have also found that leads elevated to a substantial distance from the ground, as, for instance, to a height of about fourteen feet more or less, give somewhat better results than leads close to the ground.

At the receiving station A, I have shown suitable receiving apparatus and circuits including a goniometer P, which forms a convenient instrument capable of nice adjustment for balancing out static and retaining the signals, it being understood, however, that any other suitable instruments or circuits and connections may be used to combine the effects produced as described. The stationary goniometer coils Q, as shown, are connected to the leads C extending to each cage and variable condensers T are preferably included in series with coils Q for tuning purposes. Variable tuning inductances S and variable resistances r' are shown in series with the leads. One or both of the inductances may be used as desired. The resistances may be used or omitted if not required, but at times they are found to be beneficial in making adjustments to equalize the signal or static intensity.

The movable coil R of the goniometer, rotatable about the axis U in the plane of the coils Q, is connected to suitable receiver circuits including the three-element vacuum valve V. A variable condenser W is preferably included in the circuit of the movable coil R, which also includes the loading inductance X and the coupling coil Y. The valve V is connected to the oscillatory circuit a b coupled to the coil Y. The valve has, as shown, the usual plate circuit c, d, e, f, and in addition the oscillatory circuit c, g, h, f, although any suitable and desirable circuits may be used.

By suitable adjustments of the apparatus the effects due to static disturbances neutralize and balance out, while the effects due

to the signals combine to produce a resultant current in the receiver circuits.

In addition to the tuning means shown and described in connection with the receiving apparatus, I have found that means should preferably be provided for tuning the loop antennæ or cages, and for this purpose I insert variable condensers j in the circuits of cages B, preferably at the mid points or in series between the two sets of loops L, of six loops each. If the inductance of a cage is not sufficient for tuning purposes, additional inductances (not shown) may be conveniently inserted in the connections k , for instance, but I have obtained satisfactory results with the condensers j alone, which reduces the number of elements requiring adjustment. It will also be found desirable to be able to vary the number of loops L in the cages, depending upon conditions of reception and the length of the waves received. For this purpose I conveniently and preferably provide double-throw switches o suitably connected by the wires k and p to different portions of the loops L so that by manipulating the switches more or less of the loops L may be included in circuit. Generally speaking, the number of loops L in circuit should be greater for the longer wave lengths and any suitable means may be provided for varying the number of loops L in as many steps as desired, the switches I have shown being by way of illustration only. I have found that there is a distinct advantage in providing tuning means for the antennæ in addition to tuning means in connection with the receiving apparatus, because lead troubles are reduced, the tuning is improved, and the signals increased, and it is possible to tune the antennæ or cages to the incoming signal and have the tuning means set for a given wave length, so that in working with only one transmitting station, variations in adjustments need generally only be made at the central receiving station.

Since the leads and the cages pick up both signals and static, currents are generated in each in definite directions. It has been found highly advantageous to provide means for determining the relative directions of the currents in the leads and cages, in the leads and receiving apparatus, and preferably in the receiving apparatus and the receiving circuits connected thereto. These two latter conditions become of importance in using a receiving apparatus in the form of a goniometer, but my discoveries in regard to these features may be used in connection with other forms of receiving apparatus where found applicable.

In this instance I have provided reversing switches Z^2 for reversing the connections of the leads C to the cages, and in this way I determine the relative directions of

current flowing in the leads and in the cages. Any other suitable equivalent devices could be used in place of the reversing switches. These reversing switches Z^2 enable the leads and cages to be connected so that currents in each are in the same or in opposite directions, as desired. Trial will determine which positions of the reversing switches produce the best results. The cages may be stronger than the leads requiring one position of the reversing switches Z^2 , or with greater separation between the cages and correspondingly longer leads, the leads and cages may be very nearly equal in effect, in which case it may be desirable to throw the reversing switches Z^2 so that the leads oppose the cages, thus obtaining, as is now believed, an order of balance between the leads and cages themselves in each side of the system, in which the static balances and lets through the signal. Whether or not this is the true explanation, I have nevertheless found that the reversing switches Z^2 play an important part in the tuning and balancing of the system.

I also prefer to provide reversing switches Z, or their equivalents, for reversing the connections between the leads and the receiving apparatus, which, in this instance, is a goniometer. There is apparently a best, or at least a preferable relation between the leads and the goniometer, irrespective of the relation between the leads and the cages as adjusted by the reversing switches Z^2 . This best or preferable relation seems to be determined by the effect produced on the electro-static field of the goniometer or otherwise stated, the current distribution in the coils. In operating the apparatus the switches Z^2 and Z are manipulated until the proper positions are determined for producing the best results; that is, the best balance on static and the strongest signal on proper tuning.

The function of the reversing switch Z' between the movable coil of the goniometer and the receiving circuits, is substantially similar to that of the switches Z and the position to which it is thrown probably has an effect on both the goniometer and the receiving circuits. The manipulation of this switch Z' undoubtedly has some effect on the final results produced, and is an advantage.

In order to neutralize and avoid the coupling effects between the leads C and different parts of the receiving apparatus, particularly the secondary a of the oscillation transformer, I prefer to bring the leads into the receiving house A close together and advantageously by means of lead incased cables q . As shown, these lengths of cable, containing in this instance two insulated wires with lead covering, are com-

- paratively short, preferably from fifty to one-hundred feet long, and should not be long enough to introduce complicating capacity effects. They should only be long enough to prevent actions of the nature of electro-static coupling of the outside circuits to the receiving apparatus in the receiving house. I have found that the insulation of the sheaths of the cables from one another and from the earth seems to be important, for the best results are apparently obtained when the lead sheaths are not grounded and are not connected together electrically.
- 15 My observations with the "spurious effects", as I term them, obtained in the station apparatus itself, lead me to believe with the information I at present have, that the receiving apparatus should be removed from the immediate proximity to the earth and placed at an elevation, preferably on a wooden tower, as shown in Fig. 2 for instance, in which the house A having a platform F is shown constructed on a wooden tower G of suitable construction and of a height which may be determined by the conditions present. For instance, the tower may be twenty or thirty feet high or higher if found desirable, in order to reduce the capacity of the apparatus to earth as much as possible. With the apparatus so located and well insulated antennæ and leads, the residual static will be largely eliminated. These observations will apply to any form of apparatus and antennæ or collectors for carrying out my invention in accordance with my discoveries in regard to the origin of static and method of eliminating static based on those discoveries.
- 40 In devising means for communicating between the operator at the receiving house and the operators at the cages, I have found that the leads themselves may be efficiently used for telephonic purposes without in any way interfering with the operation of the system during reception of radio signals. Accordingly, telephones *r* are shown at the cages conveniently connected across the central contacts of the reversing switches *Z*².
- 50 Similarly telephones *s* are connected to a double-throw switch *t*, the contacts of which are connected by wires *u* to the reversing switches *Z* respectively, for the leads *C* in each portion of the system, and by this means either operator at the cages may be communicated with at will by the operator at the receiving house and told to make the necessary adjustments of the tuning and controlling apparatus. Separate telephone wires could be run between the central house and cages, but this necessitates additional wire and possibly poles. The leads may also be used instead of separate wires for some suitable form of remote control in which electro-responsive devices for

adjusting the apparatus at the cages is controlled from the receiving house.

In working with my system it is to be assumed that the cages or loop antennæ *B* as located and separated an appreciable fraction of a wave length apart, lie in the general direction of desired reception. I have successfully operated, for instance, on a large scale in receiving transatlantic signals, with cages and their connecting leads lying in the general direction of a line extending by compass north-east and south-west, the desired signals coming from a northeasterly direction. One cage *B* was located in the direction substantially north-east of the receiving house and the other cage *B* was located in the direction substantially south-west of the receiving house. My receiving station was designed and erected with special reference to reception from a particular transatlantic transmitting station known to be transmitting practically continuously day and night, and sending on a wave length of 6,300 meters in the daytime and 12,600 meters at night. In order that the system should be subjected to the most severe tests practically obtainable, the receiving station was located in a semi-tropical portion of the United States and operated at a season of the year when static of all kinds is very heavy. The static was in fact so heavy for extended periods as to either entirely obliterate the signals desired to be receive or else render the reception of intelligible messages impossible with any heretofore known form of receiving apparatus.

With my system, however, substantially in the form disclosed in this specification and illustrated diagrammatically in the drawings, I was able to at all times, and with the heaviest static, obtain readable signals with great ease. Commercial or any form of useful reception would have been absolutely impossible under the conditions encountered by me with any known form of apparatus, but I was enabled to thoroughly and continuously test my system for a period of months not only under extremely adverse conditions, but by day with the shorter wave length of 6,300 meters and by night with the longer wave length of 12,600 meters. The fact that the particular transatlantic transmitting station to which I have reference was sending throughout practically the twenty-four hours daily with short intermissions, and was sending in English as well as in code, enabled me to make the most exacting tests of my invention.

The cages *B* were each located at substantially equal distances of approximately 3600 feet from the receiving house *A*. The topographical conditions were the determining factor. The effective separation of the two cages *B* was approximately 7200 feet

or about seven-tenths of a half-wave length for the 6300 meter wave, and with this separation I balanced out the static and caused the signals to add. In receiving on 5 cages B with the 12,600 meter wave, the effective separation was proportionately less, but the signals added and were readable through heavy static as with the shorter wave.

10 I also erected cages or loop antennæ B' (Fig. 5) at locations in the same general line of direction as cages B, but separated from each other by approximately 15,840 feet, in order to have an affective spacing between 15 cages of approximately one-half wave length for the long wave of 12,600 meters. These cages B' were of shorter length than cages B and were constructed substantially as shown in Fig. 5, with two 30 foot poles H 20 about 150 feet apart, having cross-arms J provided with insulators K over which was wound approximately 4080 feet of No. 10 hard-drawn copper wire, in twelve turns. Cages B' were constructed in all respects 25 substantially similarly to cages B except as to lineal dimensions, but I am not to be understood as limiting my invention to any particular type and size of loop antennæ, nor to the kind of wire employed for I am 30 describing the apparatus and constructions actually used by me with satisfactory results, and obviously variations of my constructions may be designed without departure from my invention as herein described 35 and as particularly pointed out in the claims forming a part of this specification.

The north-east cage B' was located about 8200 feet from the central receiving house A, while the south-west cage for topographic 40 cal reasons was located about 7640 feet from the receiving house, and both cages were connected to the receiving apparatus by leads C constructed similarly to those shown in Fig. 1. The circuits and connections for 45 cages B' were similar to those shown for cages B. The actual effective spacing for cages B' was approximately seven-tenths of a half-wave length for the long wave of 12,600 meters. It is to be understood that 50 my receiving station as erected and constructed with cages B and B' was capable of receiving signals from practically any high power station throughout the world on any of the wave lengths in use, whether 55 longer or shorter than either of the wave lengths mentioned which have been taken as examples, and I found that I could and actually did receive satisfactorily from transmitting stations at distances over six thousand 60 miles away, and at various angles of reception to the general north-east and south-west line of my receiving system. With either cages B or B', I have discovered 65 that signal waves arriving at substantially right angles to the line of the cages are

received and readable signals obtained while static is balanced out, but such signals grow weaker as is to be expected, the more nearly the angle of reception approaches a right angle.

In the system constructed as described, the phenomenon was observed, that the signals in the south-west cage were usually, although not invariably, louder than those in the north-east cage, and this was true, 70 whether receiving on the short 6300 meter wave or the longer 12,600 meter wave, for example. This phenomenon would continue for longer or shorter periods of time, and then at other times the signals from both 75 the north-east and south-west cages would apparently be about the same strength, and would so continue until the phenomenon referred to was again observed. For a given period of time of substantial length, other 80 things being equal, it was probably true that the south-west cage was stronger than the north-west cage for the greater part of the time. This condition seemed to be affected in some degree by the tuning of the cages 85 and the tuning at the receiving apparatus, by adjustments of the reversing switches of the system and by variations of the resistances r' at the receiving station. It was also observed that under some conditions, the 90 north-east cage appeared to be stronger than the south-west cage, and the signal from the north-east cage would be the louder, but this reversal of the phenomenon was rare 95 comparatively speaking, and would seem to be an exceptional case.

Whether or not the signals from the cages were of substantially equal loudness, made no difference in the functioning of the system, for the static at a given time was always of substantially the same strength on the north-east cage as on the south-west cages, and was balanced out and eliminated, while a readable value of signal was retained. When the signal is louder on one 100 cage than on the other, while the effects of static or strays are the same for each cage, a condition in the circuits occurs in which the ratio of signal strength to static or stray strength is apparently different in each 105 opposed portion of the system, including the cages. Obviously, however, such condition in no way alters the method of operation of my apparatus, based on my discoveries in 110 regard to static elimination.

I cannot at this time explain why the signal is sometimes louder on one cage than the other, for the causes of the phenomenon are as yet obscure, and may be due to a variety of causes. It may be that the cages and leads have some directive effect, in which case, assuming that the directivity of each half of the system is substantially similar or as near similar as mechanical and electrical construction will permit, then it might 115 120 125 130

reasonably be expected that the cage and leads which extend from the receiving house in the direction away from the source of transmission of signals, that is, the south-west cage and leads to this cage, would be the stronger and produce the louder signals. This explanation seems to accord with the observed facts, but whether or not it is the true explanation, I cannot now say, and I do 5
10 no wish to be understood as being bound by this theory. It is possible that the conditions of the ground, the height of the surface water stratum, varying geological and topographical conditions and other natural causes may have some effect. I am furthermore unable to determine at this time whether the phenomenon has any beneficial effect on the final strength or loudness of the signal received and retained, but I am 15
20 inclined to the view that the best effects are obtained when the signals are of about the same strength of loudness in each cage and with my present information I prefer to adjust the cages and circuits in such manner 25
30 that an equality between the strengths of the signals is obtained as far as possible. This equality can be obtained, or in some instances at least approximated to a very large degree, by the proper adjustments of the tuning devices and circuit controlling devices of the entire system, including the resistances r' referred to.

I have shown and described herein reversing switches with direct connections between the antennæ or cages and the leads, and between the leads and the receiving apparatus, and while this is the preferred arrangement, it is obvious that inductive coupling instead of direct coupling may be employed, and that reversible coupling means or other equivalents instead of the switches may be employed, and that these are equally within the scope of my invention.

I claim and desire to obtain by Letters Patent, the following:

1. At a radio transmission receiving station, antennæ separated by a distance equal to an appreciable fraction of a wave length and adapted to receive horizontally propagated waves, receiving apparatus associated with the antennæ for utilizing the signal waves, including means for eliminating the interference due to static disturbances, tuning means local to the antennæ and tuning means therefor in connection with the receiving apparatus.

2. At a radio transmission receiving station, antennæ separated by a distance equal to an appreciable fraction of a wave length and adapted to receive horizontally propagated waves, receiving apparatus connected to the antennæ for utilizing the signal waves, including means for eliminating the interference due to static disturbances, tuning means local to the antennæ for tuning

the antennæ to the incoming signal waves and independent tuning means therefor in connection with the receiving apparatus.

3. At a radio transmission receiving station, a plurality of loop antennæ, receiving apparatus for balancing out static disturbances while retaining the signal, leads electrically connecting the antennæ and the receiving apparatus, and means for determining the relative directions of current flow in the antennæ and leads due to static disturbances and signal waves.

4. At a radio transmission receiving station, a plurality of loop antennæ, receiving apparatus for balancing out static disturbances while retaining the signal, leads electrically connecting the antennæ and the receiving apparatus, and means for determining the relative directions of current flow in the leads and receiving apparatus due to static disturbances and signal waves.

5. At a radio transmission receiving station, a plurality of loop antennæ, receiving apparatus for balancing out static disturbances while retaining the signal, leads electrically connecting the antennæ and the receiving apparatus, and means for determining the relative directions of current flow in the antennæ and leads due to static disturbances and signal waves, and means for determining the relative directions of current flow in the leads and receiving apparatus due to static disturbances and signal waves.

6. At a radio transmission receiving station, a plurality of loop antennæ, receiving apparatus including detecting means for balancing out static disturbances while retaining and detecting the signal, leads electrically connecting the antennæ and the receiving apparatus and means for determining the relative directions of current flow in the receiving apparatus and in the circuits connected thereto including the detecting means.

7. At a radio transmission receiving station, a plurality of loop antennæ, receiving apparatus including detecting means for balancing out static disturbances while retaining and detecting the signal, leads electrically connecting the antennæ and the receiving apparatus, means for determining the relative directions of current flow in the antennæ and leads due to static and signal, and means for determining the relative directions of current flow in the receiving apparatus and in the circuits connected thereto including the detecting means.

8. At a radio transmission receiving station, a plurality of loop antennæ, receiving apparatus including detecting means for balancing out static disturbances while retaining and detecting the signal, leads electrically connecting the antennæ and the receiving apparatus, means for determining

- the relative directions of current flow in the antennæ and leads due to static and signal, means for determining the relative directions of current flow in the leads and receiving apparatus, due to static and signal, and means for determining the relative directions of current flow in the receiving apparatus and in the circuits connected thereto including the detecting means.
10. At a radio transmission receiving station, a plurality of loop antennæ, receiving apparatus including detecting means for balancing out static disturbances while retaining and detecting the signal, leads electrically connecting the antennæ and the receiving apparatus, means for determining the relative directions of current flow in the leads and receiving apparatus due to static and signal, and means for determining the relative directions of current flow in the receiving apparatus and in the circuits connected thereto including the detecting means.
11. At a radio transmission receiving station, loop antennæ separated by a distance equal to an appreciable fraction of a wave length and adapted to receive horizontally propagated waves, receiving apparatus for utilizing the signal waves, including means for eliminating interference due to static disturbances, leads electrically connecting the antennæ and the receiving apparatus, and independent means for determining the relative directions of current flow in the leads and antennæ, and in the leads and receiving apparatus, due to static and signal.
12. At a radio transmission receiving station, a plurality of loop antennæ, receiving apparatus for balancing out static disturbances while retaining the signal, leads electrically connecting the antennæ and the receiving apparatus, and means for determining the relative directions of current flow in the antennæ and receiving apparatus due to static and signal.
13. At a radio transmission receiving station, a plurality of loop antennæ, receiving apparatus for balancing out static disturbances while retaining the signal, leads electrically connecting the antennæ and the receiving apparatus, tuning means for the antennæ, tuning means in connection with the receiving apparatus, and means for determining the relative directions of current flow due to static and signal in the antennæ and receiving apparatus.
14. At a radio transmission receiving station, a plurality of loop antennæ, receiving apparatus for balancing out static disturbances while retaining the signal, leads electrically connecting the antennæ and the receiving apparatus, tuning means for the antennæ, and means for reversing the connections at will between the leads and antennæ.
15. At a radio transmission receiving station, a plurality of loop antennæ, receiving apparatus for balancing out static disturbances while retaining the signal, leads electrically connecting the antennæ and the receiving apparatus, tuning means in connection with the receiving apparatus, and means for reversing the connections at will between the leads and receiving apparatus.
16. At a radio transmission receiving station, a plurality of loop antennæ, receiving apparatus including detecting means for balancing out static disturbances while retaining and detecting the signal, leads electrically connecting the antennæ and the receiving apparatus, means for reversing the connections at will between the leads and antennæ, and independent means for reversing the connections at will between the leads and receiving apparatus.
17. In combination, at a radio receiving station, antennæ separated by a distance equal to an appreciable fraction of a wave length and adapted to receive horizontally propagated waves, receiving apparatus for utilizing the signal waves, including means for eliminating the interference due to static disturbances, leads electrically connecting the antennæ and receiving apparatus, tuning means for the antennæ and tuning means in connection with the receiving apparatus, means for reversing the connections of the leads to the antenna and means for reversing the connections of the leads to the receiving apparatus.
18. In combination, at a radio receiving station, antennæ separated by a distance equal to an appreciable fraction of a wave length and adapted to receive horizontally propagated waves, receiving apparatus for utilizing the signal waves, including means for eliminating the interference due to static disturbances, leads electrically connecting the antennæ and receiving apparatus, tuning means local to the antennæ and tuning means therefor in connection with the receiving apparatus, and means for communicating between an operator stationed at the receiving apparatus and an operator stationed at the distant tuning means for at least one antenna, thereby permitting the relative adjustments of the tuning means at the station and at one antenna.
19. In combination, at a radio receiving station, antennæ separated by a distance

equal to an appreciable fraction of a wave length and adapted to receive horizontally propagated waves, receiving apparatus for utilizing the signal waves, including means 5 for eliminating the interference due to static disturbances, and means for communicating between an operator stationed at the receiving apparatus and an operator stationed at one of the antennæ, thereby permitting relative adjustments at the station and at one 10 antenna.

20. In combination, at a radio receiving station, antennæ separated by a distance equal to an appreciable fraction of a wave length 15 and adapted to receive horizontally propagated waves, receiving apparatus for utilizing the signal waves, including means for eliminating the interference due to static disturbances, leads electrically connecting 20 the antennæ and receiving apparatus and means for utilizing the leads to communicate between an operator stationed at the receiving apparatus and operators stationed at the antennæ.

25. 21. At a radio transmission receiving station, receiving apparatus, an antenna separated therefrom at a distance, leads electrically connecting the antenna and the receiving apparatus, and means for utilizing the 30 leads to communicate between operators stationed at the receiving apparatus and antenna respectively.

22. At a radio transmission receiving station, separated loop antennæ, receiving apparatus for balancing out static and retaining 35 the signal and leads electrically connecting the antennæ and receiving apparatus, said leads lying substantially parallel and near together at a substantial elevation 40 above the ground to avoid picking up static.

23. At a radio transmission receiving station receiving apparatus, an antenna separated therefrom at a distance and leads electrically connecting the antenna and receiving 45 apparatus, that portion of the length of the leads for a substantial distance in proximity to the receiving apparatus being provided with a conducting shield to reduce coupling effects between the leads and the 50 receiving apparatus.

24. At a radio transmission receiving station, separated loop antennæ, receiving apparatus for balancing out static while retaining the signal, and leads electrically 55 connecting the antennæ and receiving apparatus, those portions of the length of the leads for substantial distances in proximity to the receiving apparatus being provided with conducting shields to reduce the coupling effects between the leads and the 60 receiving apparatus.

25. At a radio transmission receiving station, separated loop antennæ, receiving apparatus for balancing out static while re-

taining the signal, and leads electrically connecting the antennæ and receiving apparatus, said leads being arranged sufficiently close together to avoid picking up static, and tuning means at both ends of each set of 70 leads.

26. At a radio transmission receiving station, separated loop antennæ, receiving apparatus for balancing out static while retaining the signal, and leads electrically connecting the antennæ and receiving apparatus, and tuning means and reversing switches at both ends of each set of leads. 75

27. At a radio transmission receiving station, separated loop antennæ, receiving apparatus for balancing out static while retaining the signal, and leads electrically connecting the antennæ and receiving apparatus, means for varying the number of loops in the antennæ, tuning means for the antennæ and tuning means in connection with the receiving apparatus. 80

28. At a radio transmission receiving station, separated loop antennæ, receiving apparatus for balancing out static while retaining the signal, and leads electrically connecting the antennæ and receiving apparatus, means for varying the number of loops in the antennæ, and tuning means and reversing switches at both ends of each set of 95 leads.

29. At a radio transmission receiving station, separated loop antennæ, receiving apparatus for balancing out static while retaining the signal, and leads electrically connecting the antennæ and receiving apparatus, means for varying the number of loops in the antennæ, tuning means at both ends of each set of leads, and additional means at both ends of each set of leads for determining the relative directions of current flow in the leads, and in the antennæ and receiving apparatus respectively, due to static and signal. 100

30. At a radio transmission receiving station, a plurality of antennæ separated from one another by an appreciable fraction of a wave length in the general direction of desired reception, a common receiving apparatus, connections therefrom to each antenna 115 and means for determining the relative directions of the current flow in said connections and antennæ due to static and signal.

31. At a radio transmission receiving station, a plurality of separated loop antennæ, receiving apparatus and leads therefrom to said antennæ, tuning means for the antennæ, tuning means in connection with the receiving apparatus, means for determining the relative directions of current flow in the 120 antennæ and leads, and in the receiving apparatus and leads respectively, due to static and signal. 125

32. At a radio transmission receiving sta-

tion, a plurality of antennæ not connected to earth and receiving apparatus connected thereto for balancing out static disturbances while retaining the signal, said receiving apparatus being elevated at a substantial distance above the earth.

33. At a radio transmission receiving station, a plurality of separated antennæ not connected to earth, receiving apparatus, and leads connecting the antennæ and receiving apparatus so arranged as to have the same capacity to earth, said receiving apparatus being elevated at a substantial distance above the earth in order to reduce the capacity of the apparatus to earth.

34. At a radio transmission receiving station, a plurality of separated loop antennæ, and receiving apparatus connected thereto for balancing out static disturbances while retaining the signal, and tuning means con-

nected at substantially the mid-point in the length of each loop for tuning the antennæ.

35. At a radio transmission receiving station, a plurality of separated loop antennæ each having a plurality of turns or windings, receiving apparatus connected to said antennæ for balancing out static disturbances while retaining the signal, and means for varying the number of turns of the antennæ in circuit symmetrically at each side of the longitudinal center of the antenna structure.

In testimony whereof I have signed this specification in the presence of two subscribing witnesses.

ROY ALEXANDER WEAGANT.
